FLUID DISPENSING APPARATUS

Charles W. Blackburn and Herbert D. Maresh, Bartlesville, Okla., assignors to Phillips Petroleum Company, a corporation of Delaware

Application June 18, 1956, Serial No. 592,131

10 Claims. (Cl. 222—76)

This invention relates to fluid dispensing apparatus. In one aspect, this invention relates to fluid dispensing apparatus equipped with emergency shutdown means. In another aspect, this invention relates to a service station installation of fluid dispensing apparatus equipped with an emergency shutdown system.

A hazard in the operation of service stations dispensing inflammable fluid is the danger of fire occurring following an accident to a dispensing pedestal. It is not uncommon for an automobile to collide with and jar or knock over a dispensing pedestal. In such instances, dispensing conduits connecting the pedestal with the source of supply of the fluid being dispensed may be broken, in which event, there is danger of gasoline or other inflammable fluid being spilled.

In service stations wherein a plurality of dispensing pedestals are supplied from a common source by means of a single remote pump, the dispensing control switches in each dispensing pedestal are usually connected in parallel with one another in the circuit supplying current to the motor driving said pump so that closure of any single switch will energize said pump motor. Thus fluid can be dispensed from each pedestal independently of the others. With such a system, it is possible for fluid to continue to be dispensed at the other pedestals after an accident has occurred to one pedestal, even though the pedestal involved in the accident may have been equipped with means to stop the flow of fluid thereto. The danger involved is obvious. This danger is increased in those instances where the dispensing line at the pedestal is equipped with an automatic valved nozzle which automatically shuts off the flow of fluid when the customer's tank is filled. Where such equipment is used, it is common practice for the service station attendant to insert the nozzle into the automobile fuel tank and then proceed to service other parts of the automobile. In the event of an accident at an adjacent pedestal, the attendant might not be able to shut off the flow of fluid before a fire occurred. The increasing number of service station installations utilizing such automatic equipment and remote pumping facilities has caused many municipalities to require the installation of emergency shutdown equipment to eliminate or mitigate the hazards thus described.

Our invention provides fluid dispensing apparatus and/or a fluid dispensing system having emergency shutdown means. Broadly speaking, our invention comprises providing an emergency switch in each dispensing pedestal, which switch is adapted to open when said pedestal is jarred or overturned, thus opening the circuit supplying current to the motor of the fluid supply pump and shutting down the dispensing operation. In a service station where there are a plurality of dispensing pedestals, the emergency switches in the individual pedestals can all be connected in series with one another. Thus, it is possible to stop or shut down all dispensing operations when an accident occurs at any single pedestal.

It is an object of our invention to provide a dispensing

2

pedestal equipped with an emergency shutdown switch adapted to open the circuit supplying current to the supply pump motor when said pedestal is jarred, overturned, or moved from its normal operating position.

5 Another object of this invention is to provide a simple but effective control for a remote pump in a service station installation.

Still another object of this invention is to provide a fluid dispensing system capable of dispensing a fluid, or 10 different types of fluid, through a plurality of dispensing pedestals arranged in a group or groups, each said pedestal having a dispensing control switch therein, said switches being connected in parallel with one another according to said group or groups, and wherein means comprising 15 a plurality of emergency switches are provided for discontinuing the flow of fluid to one of said pedestals, a group or groups of said pedestals, or all of said pedestals, under emergency conditions.

Other aspects, advantages and objects of this invention 20 will be apparent to those skilled in the art upon reading the accompanying disclosure, claims and drawings.

Thus according to the invention, there is provided fluid dispensing apparatus comprising, in combination: at least one pump, said pump having an outlet; a motor connected 25 to drive said pump; a current source; a plurality of dispensing control switches connected in parallel with one another; a plurality of emergency switches connected in series with one another; and circuit means connecting said motor to said current source through said plurality of 30 dispensing control switches and said plurality of emergency switches.

It is to be noted that the dispensing control switches are connected in parallel with one another and the emergency switches are connected in series with one another. 35 Thus when the invention is applied to an installation having a plurality of dispensing means or pedestals, each equipped with a dispensing control switch and each equipped with an emergency switch, the dispensing operation can be carried out at any individual dispensing means 40 or pedestal by virtue of said dispensing control switches being connected in parallel with one another. However, since all of said emergency switches are connected in series with one another, an accident at any individual dispensing means or pedestal will shut down the entire dispensing operation.

45 Any number of dispensing means or pedestals can be connected into groups depending upon the different types of fluid being dispensed and the dispensing control switches and emergency switches of each group connected in parallel and in series, respectively, 50 with one another so that each group operates independently of the other groups. However, it is generally preferred that all the emergency switches of the different groups at an installation be connected in series with one another.

55 Figure 1 illustrates diagrammatically, partly in section, a service station installation having a plurality of dispensing pedestals wherein said pedestals are all supplied with the same type of fluid. The dispensing control switches are connected in parallel with one another and the emergency switches are connected in series with one another 60 in circuit means connecting the motor driving the fluid supply pump with a current source.

Figure 2 illustrates a schematic wiring diagram for a 65 service station installation where two different types of fluid are dispensed through a plurality of groups of dispensing pedestals. The dispensing control switches of each group are connected in parallel with one another and the emergency switches of each group are connected in series with one another.

70 Figure 3 is a schematic wiring diagram similar to that illustrated in Figure 2 except that all of the emergency

switches of all groups of pedestals are connected in series with one another.

Figure 4 illustrates a schematic wiring diagram similar to that shown in Figure 2.

Figure 5 illustrates a schematic wiring diagram similar to that shown in Figure 3.

Like reference numerals are employed to designate like elements in the several drawings. The reference numerals given in Figure 1 for dispensing pedestal 27 apply to like elements in dispensing pedestal 28 where the reference numerals have been omitted for the sake of clarity.

Referring to Figure 1, a storage tank 10 is shown containing liquid fuel 11. Storage tank 10 is buried in the earth 12 and at least a portion of the earth is covered by a concrete slab 13. Tank 10 is provided with a filling line 14 having a suitable filling cap 15 located in a recess 16 of slab 13. Said recess can be closed for convenience by means of trap door 17. Tank 10 can also be provided with a vent line 18 so as to vent vapors therefrom to the atmosphere. Said vent line is customarily located at a distance from the remainder of the installation and can be provided with a suitable rain cap 19. In some installations, said vent pipe 18 is not provided and tank 10 operates under the vapor pressure of the liquid stored therein. A suitable pump and motor assembly 20 is disposed within said tank 10 and submerged in fluid 11. A conduit 21 connects said pump and motor 20 with outlet 22 disposed without said tank 10. A suitable connecting terminal 23 is provided in recess 16 for the connection of lead wires from a current source (described hereinafter) to said motor and pump assembly 20. Suitable conduit or cable means (not shown) within conduit 21 provide a connection between connecting terminal 23 and the motor of pump and motor assembly 20. Although the lead wires to connecting terminal 23 are shown extending through trap door 17 for purposes of simplicity, it will be understood by those skilled in the art that said lead wires are usually placed in a conduit which would extend through slab 13 and a side wall of recess 16.

A discharge line 24 is connected to pump outlet 22 and provides communication between said pump outlet and dispensing lines 25 and 26 as shown. Each dispensing line 25 and 26 leads to a separate dispensing pedestal, designated generally as 27 and 28, respectively. While only two dispensing pedestals are here shown, it will be understood that any number of said pedestals can be employed, and further, that said pedestals can be arranged in any convenient manner in any convenient number of groups. Said dispensing pedestals are commonly referred to by the public as "gas pumps" but they are referred to herein as dispensing pedestals because the actual pump is located remotely from the dispensing pedestal. Each of said pedestals comprises a housing 29, and a meter 30 disposed within said housing in each dispensing line 25 and 26. The downstream portions 31 of said dispensing lines are customarily made of a suitable flexible material and terminate in a valved nozzle 32 having a suitable trigger mechanism 33 therein for opening said valve. Said meters 30 measure the amount of fluid passing through dispensing lines 25 and 26, and each meter is operatively connected by means of a connection 34 to an indicator 35. Said meter 30 can be any suitable type of meter from the prior art which will meet the requirements of the law in the particular jurisdiction involved and can be adapted to measure the amount of fluid dispensed either by volume or by weight. Indicator 35 indicates the amount of fluid passing through line 25 or line 26 and can read in terms of amount on one set of odometer-type discs 36, and as to price on another set of odometer-type discs 37. While not necessary to the invention, it is commercially preferable to have means 38 to reset said odometer-type discs 36 and 37 with each purchase.

Valved nozzle 32 rests in the bifurcated end of movable member 39 which is pivoted at 40 so that when said

valved nozzle is lifted, said movable member 39 is forced upward by means of spring 41. Mercury tilt switch 42 (dispensing control switch) is attached to and rests upon said movable member 39 so that when the latter is forced upward the mercury 43 in said switch is displaced to the other end of its container and completes the circuit between electrical wires 44 and 45. The combination of movable member 39, spring 41, switch 42, mercury 43, and the ends of wires 44 and 45 which are inside the switch 42, represent and serve as a normally closed switch which is biased into open position by the weight of nozzle 32 resting in the extended bifurcated end of movable member 39. An emergency switch 46 is disposed within the lower portion of housing 29. Said switch 46 is attached to said housing 29 by any convenient means such as bolts 67. The particular switch 46 here illustrated is a conventional switch of the type EX-XR3 sold commercially by Micro Switch, a division of Minneapolis-Honeywell Regulator Company, Freeport, Ill. Said switch 46 comprises an explosion-proof housing having the actual switch means mounted therein, and an actuator arm 47, having a roller 48 in the end thereof, extending from one side of said switch housing. Said roller 48 rests upon bolt 49 which is supported by bracket 50 attached by means of an anchor bolt to the wall of a recess in slab 13 over which housing 29 is mounted. Bolt 49 is adjustable with respect to height above bracket 50 by means of nut 51. Switch 46 is a normally open switch which is biased into closed position by arm 47 resting on bolt 49.

Circuit means are provided for connecting the motor of motor and pump assembly 20 through dispensing control switches 42 and emergency switches 46 with a current source 52. Tracing said circuit means from said current source 52 starting with wire 53, it will be noted that wire 53 connects with wires 44 leading to dispensing control switches 42 in each of dispensing pedestals 27 and 28. Wires 45 lead from said switches 42 in each of said pedestals 27 and 28 connect with wire 54 which in turn connects with one terminal of connecting terminal 23. The other terminal of said connecting terminal 23 is connected to wire 55 which is connected to one terminal of the emergency switch 46 in pedestal 27. Wire 56 is connected to the other terminal of said switch 46 and leads to the emergency switch 46 in pedestal 28. Wire 57 from said last mentioned switch 46 connects with wire 58 which in turn is connected to the other pole of current source 52. Tracing said circuit as outlined, it is seen that the dispensing control switches 42 in said pedestals 27 and 28 are connected in parallel with one another whereas the emergency switches 46 in said pedestals 27 and 28 are connected in series with one another.

Figure 2 illustrates a schematic wiring diagram suitable for use where two grades of fluid are to be dispensed from two different groups of dispensing pedestals. Each of dispensing control switches 42 is a mercury tilt switch of the type described in connection with Figure 1. Each of emergency switches 46 is of the same type as described in connection with Figure 1. It will be understood that there is one dispensing control switch 42 and one emergency switch 46 in each dispensing pedestal. Thus the wiring diagram illustrated in Figure 2 is for two groups of four dispensing pedestals each, each group being supplied from a separate storage tank by means of separate pump and motor assemblies 20 and 20' connected to a common current source 52 through switches 42 and switches 46 of each group. Tracing the circuit similarly as in connection with Figure 1, it will be seen that the dispensing control switches 42 in each group are connected in parallel with one another and that the emergency switches 46 in each group are connected in series with one another. Thus when the dispensing pedestals are connected as in Figure 2, the two groups of pedestals operate independently.

Referring to Figure 3, there are illustrated two groups of dispensing pedestals connected in the same manner as

in Figure 2 insofar as the dispensing control switches 42 are concerned. However, it will be noted that all of the emergency switches 46 are connected in series with one another. Thus when the dispensing pedestals are connected as in Figure 3, each group operates independently of the other group insofar as the dispensing control switches 42 are concerned, but all the groups are connected together through said emergency switches 46 which are connected in series with one another. Therefore an accident at any dispensing pedestal will shut down pumping operations for the entire installation.

Figures 4 and 5 are like Figures 2 and 3, respectively, except that relay means 60 and master switch 61 are provided. It will be noted that current in a branch of said circuit means flows through relay means 60 when all of the emergency switches 46 are closed and the solenoid of relay means 60 holds master switch 61 in closed position. Said master switch 61 is normally biased to an open position by means of spring 62.

In the operation of the system illustrated in Figure 1, assume that an automobile is being serviced at dispensing pedestal 27 and that nozzle 32 is delivering gasoline into the fuel tank of said automobile. Assume further that another automobile entering the service station strikes and knocks over dispensing pedestal 28. Since emergency switch 46 in dispensing pedestal 27 and emergency switch 46 in dispensing pedestal 28 are connected in series with one another in the circuit means supplying current to the motor of motor and pump assembly 20, emergency switch 46 in dispensing pedestal 28 will immediately open said circuit and shut down the delivery of gasoline at dispensing pedestal 27. The opening of said circuit by switch 46 is effected because actuator arm 47 of said switch is moved off of bolt 49 and travels downwardly thereby opening the switch means within the explosion-proof housing of said switch 46. It will be noted that said bolt 49 is attached to bracket 50 which in turn is attached to a wall of the recess in concrete slab 13 and being thus attached independently of the housing 29 of dispensing pedestal 28 does not move when said housing is moved.

If the dispensing pedestals of the service station installation are connected in the manner illustrated in Figures 2 and 4, i. e., a plurality of independent groups, an accident at one of said dispensing pedestals will shut down dispensing operations at only the other dispensing pedestals of the same group. For this reason, the method of connecting the dispensing pedestals illustrated in Figures 1, 3, and 5 is preferred because an accident at any dispensing pedestal will open the emergency switch in said dispensing pedestal and shut down operations at all of said dispensing pedestals.

While the invention has been illustrated as applied to service station installations dispensing two grades of fuel, it will be understood by those skilled in the art that the invention is not so limited. Any number of dispensing pedestals suitably arranged in groups similarly as described above can be employed to dispense any number of different types of inflammable fuel.

The invention is also applicable to dispensing operations other than service station installations.

Mercury tilt switch 42 is of the type well known to those skilled in the art. Said switch 42 usually comprises an electrically non-conducting curved chamber containing some mercury 43. Any suitable type of a mercury tilt switch or any other suitable type of a normally closed explosion-proof switch can be employed in the service illustrated for switch 42.

Emergency displacement switch 46 can be any suitable type of normally open explosion-proof switch. The type here illustrated is merely the presently preferred type. It is generally preferred that such switches be of the type requiring manual reset so as to take care of those situations wherein the dispensing pedestal would be merely "tipped" or "rocked" and then return to its normal upright position. If switch 46 were not of the type

requiring manual resetting, it is possible that actuating arm 47 could again come to rest on bolt 49 and restore the circuit which would cause gasoline or other inflammable fluid to be pumped through the system and out through any breaks which may have occurred in the dispensing line, such as dispensing line 25. The type of switch 46 here illustrated can be manually reset by turning actuating arm 47 slightly in a counter clockwise direction.

While a submerged pump and motor assembly 20 has been illustrated in tank 10, it will be understood by those skilled in the art that a submerged pump and motor is not required. The system of the invention is equally applicable to any suitable type of pump and motor regardless of whether it is a surface type or submerged type.

Various other modifications and embodiments of the invention will be apparent to those skilled in the art in view of the above disclosure and the attached drawings. Such modifications are within the spirit and scope of the invention.

We claim:

1. Fluid dispensing apparatus comprising, in combination: at least one pump, said pump having an outlet; a motor connected to drive said pump; a current source, a plurality of dispensing control switches connected in parallel with one another; a plurality of emergency switches connected in series with one another; and circuit means connecting said motor to said current source through said plurality of dispensing control switches and said plurality of emergency switches so that said motor is disconnected from said current source whenever any one of said emergency switches is opened.

2. Fluid dispensing apparatus comprising, in combination: at least one pump, said pump having an outlet, a motor connected to drive said pump; a current source; a plurality of dispensing conduits; a plurality of dispensing control switches connected in parallel with one another and adapted to coact with said dispensing conduits, one switch for each conduit, and energize said motor when a dispensing conduit is activated; a plurality of emergency switches connected in series with one another and adapted to deenergize said motor under emergency conditions; and circuit means connecting said motor to said current source through said plurality of dispensing control switches and said plurality of emergency switches so that said motor is disconnected from said current source whenever any one of said emergency switches is opened.

3. A fluid dispensing system comprising, in combination: a plurality of dispensing pedestals supplied with fluid from at least one pump, each of said pedestals comprising a housing and a dispensing conduit terminating in a valved dispensing nozzle; a motor connected to drive said pump; a current source; a dispensing control switch mounted within the housing of each said pedestal and adapted to coact with the said dispensing nozzle and energize said motor when said nozzle is activated; an emergency switch attached to each said housing adapted to deenergize said motor when said housing is moved from its normal position; and circuit means connecting said motor to said current source through said dispensing control switch and said emergency switch.

4. Fluid dispensing apparatus comprising, in combination: a plurality of pumps, each pump having an outlet; a motor connected to drive each pump; a current source; a plurality of dispensing conduits arranged in a plurality of groups, each group connected to the outlet of one of said pumps; a plurality of dispensing control switches, arranged in groups corresponding to said groups of dispensing conduits, the switches in each group connected in parallel with one another, and adapted to coact with said dispensing conduits, one switch for each dispensing conduit, and to energize said motor when a dispensing conduit is activated; a plurality of emergency switches, arranged in groups corresponding to said groups of dispensing conduits, the switches in each group connected in series with one an-

other, one switch for each dispensing conduit, and adapted to deenergize said motor under emergency conditions; and circuit means connecting each motor of each group to said current source through said plurality of dispensing control switches for each group and said plurality of said emergency switches for each group so that said motor of each group is disconnected from said current source whenever any one of said emergency switches for each group is opened.

5. Fluid dispensing apparatus comprising, in combination: a plurality of pumps, each pump having an outlet; a motor connected to drive each pump; a current source, a plurality of dispensing conduits arranged in a plurality of groups, each group connected to the outlet of one of said pumps; a plurality of dispensing control switches, arranged in groups corresponding to said groups of dispensing conduits, the switches in each group connected in parallel with one another, and adapted to coact with said dispensing conduits, one switch for each dispensing conduit, and to energize said motor when a dispensing conduit is activated; a plurality of emergency switches, connected in series with one another, one switch for each dispensing conduit, and adapted to deenergize said motor under emergency conditions; and circuit means connecting each motor of each group to said current source through said plurality of dispensing control switches for each group and said plurality of said emergency switches so that said motor is disconnected from said current source whenever any one of said emergency switches is opened.

6. Fluid dispensing apparatus according to claim 4 wherein said emergency switches are in a branch of said circuit means having relay means therein, said relay means being adapted to cause a normally open master switch in said circuit means to open when one of said emergency switches opens.

7. Fluid dispensing apparatus according to claim 5 wherein said emergency switches are in a branch of said circuit means having relay means therein, said relay means being adapted to cause a normally open master switch in said circuit means to open when one of said emergency switches opens.

8. A service station fluid dispensing installation comprising, in combination: a plurality of pumps, each pump having an outlet; a motor connected to drive each pump; a current source; a plurality of dispensing pedestals arranged in a plurality of groups, each group connected to the outlet of one of said pumps, and each of said dispensing pedestals comprising a housing and a dispensing conduit terminating in a valved dispensing nozzle; a dispensing control switch mounted within the housing of each said pedestal and adapted to coact with the said dispensing

nozzle and energize said motor when said nozzle is activated; an emergency switch attached to each said housing adapted to deenergize said motor when said housing is moved from its normal position; said dispensing control switches in each group of said dispensing pedestals being connected in parallel with one another; said emergency switches in each group of dispensing pedestals being connected in series with one another; and circuit means connecting the pump motor for each group of pedestals to said current source through the plurality of dispensing control switches for each said group of pedestals and the plurality of emergency switches for each said group of pedestals.

10 9. A service station fluid dispensing installation comprising, in combination: a plurality of pumps, each pump having an outlet; a motor connected to drive each pump; a current source; a plurality of dispensing pedestals arranged in a plurality of groups, each group connected to the outlet of one of said pumps, and each of said dispensing pedestals comprising a housing and a dispensing conduit terminating in a valved dispensing nozzle; a dispensing control switch mounted within the housing of each said pedestal and adapted to coact with the said dispensing nozzle and energize said motor when said nozzle is activated; an emergency switch attached to each said housing adapted to deenergize said motor when said housing is moved from its normal position; said dispensing control switches in each group of said dispensing pedestals being connected in parallel with one another; said emergency switches in all of said dispensing pedestals being connected in series with one another; and circuit means connecting the pump motor for each group of pedestals to said current source through the plurality of dispensing control switches for each said group of pedestals and said plurality of emergency switches.

15 10. A service station dispensing pedestal comprising, in combination: a housing; a dispensing conduit terminating in a valved dispensing nozzle; a meter mounted within said housing and disposed in said dispensing conduit; a dispensing control switch mounted within the housing of said pedestal and adapted to coact with said dispensing nozzle and energize a first supply pump motor when said nozzle is activated; and an emergency switch attached to said housing adapted to deenergize said motor when said housing is moved from its normal position.
